European Patent Office Search Report of Application No. 10814054.2; mailed on May 27, 2013.

Primary Examiner — Phillip S Hyder(74) *Attorney, Agent, or Firm* — David Lewis; Bowen Liu(57) **CLAIM**

The ornamental design for a cutting tool, as shown and described.

DESCRIPTION

FIG. 1 is a top perspective view of a cutting tool.

FIG. 2 is a front perspective view of the cutting tool; and, FIG. 3 is a side perspective view of the cutting tool.

The design disclosed herein is intended to be used as a cutting tool, and the cutting may be performed under water. The regions that are bounded with dashed lines demarcate regions that are not being claimed and form no part of the claimed invention. Similarly, the structures drawn in phantom using dashed lines are not being claimed and form no part of the claimed invention.
